US00D976981S

(12) **United States Design Patent** (10) **Patent No.:** **US D976,981 S**
(45) **Date of Patent:** **** Jan. 31, 2023**

(54) **INDUSTRIAL ROBOT**

- (71) Applicant: **Beijing Siling Robot Technology Co., Ltd.**, Beijing (CN)
- (72) Inventors: **Daniel Duerr**, Munich (DE); **Hernan Herrero**, Munich (DE); **Zhaopeng Chen**, Beijing (CN); **Tian Li**, Beijing (CN); **Hairong Wang**, Beijing (CN); **Xiang Li**, Beijing (CN)

(**) Term: **15 Years**

(21) Appl. No.: **35/514,785**

(22) Filed: **Jul. 6, 2022**

(80) **Hague Agreement Data**

Int. Filing Date: **Jul. 6, 2022**

Int. Reg. No.: **DM/222189**

Int. Reg. Date: **Jul. 6, 2022**

Int. Reg. Pub. Date: **Jul. 29, 2022**

(30) **Foreign Application Priority Data**

Jan. 7, 2022 (CN) 202230008927.5

(51) **LOC (14) Cl.** **15-99**

(52) **U.S. Cl.**

Primary Examiner — Mojtaba Tehrani

(57) **CLAIM**

The ornamental design for an industrial robot, as shown and described.

DESCRIPTION

The patent or application file contains at least one drawing executed in color. Copies of this patent or patent application publication with color drawing(s) will be provided by the Office upon request and payment of the necessary fee.

1. Industrial robot

1.1 : Perspective

1.2 : Front

1.3 : Back

1.4 : Top

1.5 : Left

1.6 : Right

The blue color background shown in the reproductions is for the purpose of illustrating unclaimed environment only and forms no part of the claimed design.

1 Claim, 6 Drawing Sheets
(6 of 6 Drawing Sheet(s) Filed in Color)
